UNITED STATES PATENT OFFICE.

NATHANIEL B. WALES, OF BOSTON, MASSACHUSETTS, ASSIGNOR, BY MESNE ASSIGNMENTS, TO SELAW PRODUCTS COMPANY, OF SAGINAW, MICHIGAN, A CORPORATION OF MICHIGAN.

ROTARY VALVE FOR EXPLOSION-ENGINES.

1,180,346.

Specification of Letters Patent. Patented Apr. 25, 1916.

Application filed March 29, 1912. Serial No. 687,197.

To all whom it may concern:

Be it known that I, NATHANIEL B. WALES, a citizen of the United States of America, residing at Boston, in the county of Suffolk and State of Massachusetts, have invented certain new and useful Improvements in Rotary Valves for Explosion-Engines, of which the following is a specification, reference being had therein to the accompanying drawings.

The invention relates to explosion engines of the rotary valve type and has for its object; first, the perfect balancing of the valve; second, to effectively seal about the ports so as to prevent leakage; third to minimize frictional losses; and fourth, to avoid the necessity of close fits and the difficulties incident to the unequal expansion and contraction of the metal.

With these and other objects in view the invention consists in various features of construction as hereinafter set forth.

In the drawings;—Figure 1 is a vertical central cross section through one of the cylinders and valve of an explosion engine; Fig. 2 is a longitudinal section thereof with the valve shown in elevation; Fig. 3 is a side elevation of the valve; Figs. 4, 5 and 6 are cross sections therethrough on line $x-x$, $y-y$, $z-z$ respectively; Fig. 7 is a longitudinal section through one of the sealing rings; and Fig. 8 is an elevation thereof.

A is the casing of an explosion engine preferably of the integral multi-cylinder type, B is a head preferably integral with the cylinders and which forms a case for a longitudinally extending rotary cylindrical valve C. The latter is common to all of the several cylinders and is driven in properly timed relation by suitable mechanism such as the spiral gears D and shaft E, which in turn is driven from the crank shaft (not shown).

One of the objects of the invention is to maintain the valve in perfect balance and to this end the gases are introduced and exhausted from each of the cylinders by way of ports arranged on diametrically opposite sides of the valve and of equal area. These ports communicate with inlet and exhaust passages formed interiorly of the valve, being separated from each other by suitable partitions and communicating respectively with inlet and exhaust passages in the casing B. As shown, F and F' are the dia-

metrically opposite ports both of which are in constant communication with the explosion chamber. G and G' are the co-operating inlet ports in the valve and H and H' are the corresponding exhaust ports. All of the valve ports communicate with the interior of the valve but the ports G and G' are in communication with a chamber I, while the ports H and H' are in communication with the chamber J separated from the chamber I by a partition K. The ports for each engine cylinder are all in circumferential alignment and are spaced and proportioned to register the pairs alternately with the ports F, F' and in properly timed relation, the valve rotating preferably at one quarter crank shaft speed.

The engine casing is provided with suitable inlet and exhaust manifolds, these being formed in the integral head and connected to the chambers within the valve at different points in the length thereof. As shown, the inlet passage L extends longitudinally of the valve case B above the valve and communicates with the chamber I through a circumferential series of ports M in the valve. In a similar manner the exhaust chamber J communicates through an annular series of ports N in the valve with the exhaust passage O in the casing B.

With the construction as thus far described it will be understood that the pairs of opposed ports F, F' of equal area and which are in constant communication with the engine cylinder will perfectly balance the gaseous pressures exerted upon the valve. There are however, other difficulties to be overcome, one of which is the distortion of the valve and its case through unequal beating of portions thereof. This necessitates the provision of considerable clearance between the valve and its seat to avoid binding of the parts and which in turn results in leakage and loss of pressure. Furthermore, even with sufficient clearance there is a considerable element of friction. I have overcome these difficulties by providing a clearance between the valve and its case sufficient to prevent any direct contact therebetween, while the valve is journaled in external bearings preferably anti-friction bearings of the ball or roller type and which hold it in concentric relation to its case. To prevent leakage through the clearance space, sealing means is provided surrounding the ports in

communication with the engine cylinders. This sealing means is preferably automatically adjusted into gas tight contact with the valve by partially balanced pneumatic pressure. In detail, P are the anti-friction journal bearings for the valve located in extensions Q at opposite ends of the case B, R are the pneumatically operated sealing devices which are located in the ports F and F' and 10 are provided with valve contacting segmental surfaces S extending uninterruptedly completely around the port. A seal is also formed between the member R and the wall of the recess in which it is located and 15 the area exposed to pressure toward the valve is so proportioned to the area exposed to an opposite pressure as to produce a slight differential in favor of the former.

The specific construction of sealing means 20 preferably between the member R and the wall of the recess preferably employed, is a thin wall T which tapers to a knife edge and has just sufficient clearance with the wall of the recess as to be freely movable. This will 25 be slightly expanded by the pressure of explosion to complete the seal, and upon the exhausting of pressure the resiliency of the metal will restore the wall to its normal dimension, again providing sliding clearance. 30 The thin wall T is preferably circular in form but the ports F and F' are necessarily in the form of a comparatively narrow and elongated slot which necessitates the change of form of the member R between the wall 35 T and the bearing face S, as shown in Figs. 7 and 8.

In alignment with the diametrically opposite ports, detachable cap members of sufficient size to permit of the insertion of the 40 sealing means are positioned in the head.

In operation, whenever the gaseous pressure is developed within the engine cylinder either during the compression stroke or after explosion, the members R will be pressed into sealing contact with the valve face by 45 the differential pneumatic pressure and will simultaneously be sealed against the wall of the recess by the expansion of the thin flange T. This will effectually prevent leakage of the compressed gases while at the same time 50 the valve remains out of contact with its case even where there is a distortion by the heat of explosion. As soon as the pressure within the cylinder falls to atmosphere all pressure of the member R against the valve is 55 relieved, thereby reducing the wear.

What I claim as my invention is:

The combination with the cylinder of an explosion engine, of a cylindrical valve case within the head of the engine extending 60 across the cylinder, provided with diametrically opposite ports in communication therewith and with inlet and exhaust passages, a valve within said case having inlet and exhaust ports adapted to communicate with said opposite ports, means surrounding said opposite ports for sealing between said valve and the case, and detachable cap members in the head of the engine in alignment with said opposite ports, said 65 cap members being of sufficient size to permit of the insertion of the sealing means directly into positions for sealing their respective ports.

In testimony whereof I affix my signature 75 in presence of two witnesses.

NATHANIEL B. WALES.
